UNITED STATES PATENT OFFICE.

PHILIP SWETT KIMBALL, OF MILFORD, MASSACHUSETTS.

JACK.

1,225,822.

Specification of Letters Patent.

Patented May 15, 1917.

Application filed December 16, 1916. Serial No. 137,279.

To all whom it may concern:

Be it known that I, PHILIP S. KIMBALL, a citizen of the United States, residing at Milford, in the county of Worcester and State of Massachusetts, have invented an Improvement in Jacks, of which the following is a specification.

This invention relates to extension operating handles for jacks of the type described and claimed in my application filed May 22, 1915, Serial No. 29,891.

The jack of the said application is of the screw type, wherein the lifting element is threaded for co-operation with geared connections, in turn rotated through a handle. In the structure referred to the handle was of the extensible form through telescopic relation of its tubular component sections. It is desirable, however, to provide a handle of greater operating strength in rotary movement than such hollow collapsible handle, and to further construct the handle in such manner that its extensible elements may be completely separated from the jack for convenient storage, and adapted to be folded into compact form.

The object of the present invention is, therefore, the provision of a separable, foldable, handle for such jack, or any other jack with which it may be used, adapted for pivotal connection with the gear connections thereof.

The invention consists essentially in a short main section permanently connected with the jack and adapted for pivotal connection with the driving gear-element thereof, and a folding extension element or handle adapted for detachable connection with the aforesaid permanent section, said extension element, when detached from the permanent section, being adapted to be folded into compact form; and said extensible element bearing hand gripping members, which members are or may be pivotally connected to the end of one of the sections and adapted to be brought into parallel relation therewith when out of use and to be swung outward into angular position with respect thereto when in use.

In the drawings:—

Figure 1 is a side elevation of a jack having a handle embodying this invention.

Fig. 2 is a longitudinal sectional view of the permanent section.

Figs. 3 and 4 are plan and side views, respectively, of the extension element removed,

Fig. 5 is a transverse section taken on the line 5—5, Fig. 4.

The jack, indicated generally at 1, is here shown of the type illustrated in the application before referred to, includes as the only necessary adjunct for the purpose of the present invention, a permanent jack-handle section 2, adapted to be rotated in the operation of the jack. Such section 2 is 60 preferably pivotally mounted at the jack-end, as at 3, and temporarily held in extended relation through a ball-and-socket lock 4, as shown in Fig. 2.

An extension element is adapted for detachable connection with the permanent handle section 2, preferably by a sliding joint and to be held by a spring locking element. Said extension element, as here shown, comprises a plurality of sections, two 70 being shown at 5 and 6. The sections 5 and 6 are pivotally connected at their meeting ends, through a pivot structure involving a lug 7, projecting from one section fitted between ears 8 formed on the other section. 80 Both the lug and ears are laterally enlarged, as at 9, to permit the pivot-pin 10 to center beyond the longitudinal planes of the similar surfaces of the sections when extended. By reason of the relatively offset pivot, the 85 sections may fold into parallel or substantially parallel relation, for providing a compact, comparatively short structure, very conveniently stored in restricted areas, as the usual automobile tool-box. The sections 90 at the inner terminals of the lug and ears are formed to present abrupt or square ends or portions 11, 11, adapted to engage, when the sections are extended and limit the opening movement to alined positions of such 95 sections.

The free end 12 of one section, as 5, is of non-circular cross-section, and is adapted to fit into a correspondingly shaped and sized socket 13 of the jack-handle section 2. 100 A lock is provided to secure such connection against accidental separation, being shown as preferably comprising a leaf spring 14, secured to the section 5, such spring, near its free end being formed to present an 105 offset lug 15, engaging when the handle is in place in an annular recess 16 in the section 2. The resiliency of the spring maintains the lock, while at the same time such form of lock will additionally serve to advise the 110 user when the sections have been properly coupled.

The free end of the section 6 has laterally extended lugs 17, to which are pivotally connected short hand-bars or grips 18. The grips are preferably formed with terminal ears 19, arranged wholly to one side of the longitudinal medium plane of the grip, and such ears are arranged respectively on opposite sides of the lugs 17 of the section 6. The lugs 17 are in a plane parallel to the plane of the pivot-pin 10 of the sections to avoid interference in folding, and positioned to permit the hand grips, when folded, as they are adapted to be when not in use, to lie in the general direction of and 15 but slightly beyond the handle sections, see Fig. 3.

With the described handle a jack of the screw or similar type may be operated with comparative ease under comparatively great 20 load strain, owing to the leverage offered. Furthermore, the extensible handle permits the operation of the jack from positions sufficiently far from the actual jack position, as to enable the user, in the great majority 25 of instances of use of the jack in automobile work, to stand beyond the car body or wheels, and hence avoid the usual dirt and inconveniences attending the use of the ordinary jack. The inconveniences noted are 30 avoided in no small degree by the capability of the present handle as a means, practically rigid in one relation, of positioning the jack or removing it from beneath the car, without necessity of the usual direct hand application.

The section 5 may have a lug 20, adjacent its free end, for convenience in driving such handle from the jack-handle section 2, if necessary.

40 I claim:—

1. An extension handle for screw jacks comprising sections having complementary flat interlocking end-portions carried by said

section, a pivotal connection between said end portions offset from and at right angles 45 to the axial line of the sections, whereby the sections may be closely folded together, each end-portion having a square end face and a square shoulder disposed on opposite sides of the pivotal connection, the end face and shoulder of the end portion of one section being adapted to engage a shoulder and end face respectively of the end portion of the other section to limit the movements of said sections in one direction to a substantially alined position, said complementary end portions, when said faces and shoulders are in engagement, serving to transmit a rotary motion from one section to the other, and grip members carried by one section. 60

2. An extension handle for screw jacks comprising two sections, complementary interlocking end-portions carried by said sections, a pivotal connection between said end portions offset from and at right angles to 65 the axial line of the sections, whereby said sections may be closely folded together, square end-faces and shoulders disposed on said end portion on opposite sides of the pivotal connection, adapted for engagement 70 to limit the angular movement of the sections in one direction, and pivotally supported hand grips carried by the free terminal of the other section, the pivots of the hand grips being permanently perpendicular to the pivot of the sections to permit the section and hand grips to be folded into compact relation without interference. 75

In testimony whereof, I have signed my name to this specification, in the presence of two subscribing witnesses.

PHILIP SWETT KIMBALL.
